JOHN E. McLAUGHLIN, OF TOLEDO, OHIO, ASSIGNOR TO OWENS-ILLINOIS GLASS COMPANY, OF TOLEDO, OHIO, A CORPORATION OF OHIO

GLASSWARE FORMING MACHINE

Application filed November 3, 1928. Serial No. 316,935.

The present invention relates to improvements in machines for forming hollow glassware. More particularly the invention relates to improved means for actuating the holding means by which bottles or the like articles are held against premature movement during and for a predetermined period after opening of the finishing molds.

In the modern suction type machine for forming hollow glassware such as bottles, the article holder or "knock-out arm" as it is referred to in the trade, cooperates with the bottom plate of the finishing mold in preventing premature lateral or other movement of the articles. Without this "knock-out" or holding arm bottles or similar articles frequently stick to one of the mold sections and are moved thereby in such a fashion that they are not properly discharged from the machine, the result being that the articles become broken or so distorted that they cannot be used. This holding arm prevents such movement of the articles and when accurately adjusted insures discharge of the articles from the forming machine at the proper point.

These holding arms which are individual to the finishing molds are periodically swung in an arc to bring disks carried by the arms to positions over the upper end of articles in the finishing mold. Immediately following such positioning of the disks the latter are moved axially into contact with the article. Ordinarily the swinging movement of the arm is obtained thru engagement between a stationary cam and portions of the carrier for the holding arm. Because of necessarily limited amount of space allotted to this cam it has been necessary to shape the cam to quickly move the knock-out arms to and from their operative positions. The increased speed at which machines are at present operated has proportionately increased the speed of operation of the holding arms with the result that the latter are subjected to quite severe strains and wear.

Another objection to such operation of the bottle holding arm, resides in the difficulty often experienced in maintaining proper relation between the cams controlling the position of the arm over the bottles or other

articles, and the serpentine track which alternately raises and lowers the finishing mold units. Unless these cams are quite accurately positioned with respect to each other and the serpentine track and always maintained in such positions, the holding disks which seat upon the bottles or similar articles in the finishing molds are subject to vibration or lateral movement of a degree to distort or scratch the finish or sealing ends of the bottles. Such glassware is unfit for commercial use.

An object of the present invention is to avoid the above objections by providing novel means to position the disks over the articles in the finishing mold, said means being capable of efficiently performing its function irrespective of its relation to the serpentine track which raises and lowers the finishing molds.

Another object is to provide improved means for oscillating the holding arm, said means embodying a safety device insuring inoperative positioning of the arm under abnormal operating conditions.

A further object is to provide novel and easily adjustable means to control the degree of oscillatory movement of the knock-out arm to thereby insure accurate positioning of the holding disks over the articles in the finishing molds.

Other objects will be apparent hereinafter.

In the drawings:

Fig. 1 is a fragmentary plan view of the invention shown in conjunction with a finishing mold head.

Fig. 2 is a side elevation thereof with parts in section.

Fig. 2A is an elevation showing the disk lowering cam and means to adjust the latter.

Fig. 2B is a sectional view of the cam adjusting means taken along the line IIB—IIB of Fig. 2A.

Fig. 3 is a detail fragmentary elevation with parts in section showing the means for actuating the holding arm.

Fig. 4 is a fragmentary side elevation looking at the righthand side of Fig. 3.

Fig. 5 is a sectional view taken along the

line V—V of Fig. 8, the cover plate being in operative position.

Fig. 6 is a plan view of the valve mechanism for controlling the air under pressure.

5 Fig. 7 is a sectional view taken along the line VII—VII of Fig. 6.

10 Fig. 8 is a fragmentary elevation of the side shown in Fig. 3, the cover plate being removed to disclose the rack and pinion mechanism which oscillates the "knock-out arm."

15 Fig. 9 is a fragmentary sectional view of a portion of the means for raising and lowering the holding arm.

15 Fig. 10 is a sectional view taken along the line X—X of Fig. 9.

20 Fig. 11 is a fragmentary elevation showing the adjustable means by which the extent of oscillation of the holding arms may be predetermined.

25 In the drawings illustrating the preferred embodiment of the invention the latter is shown associated with a bottle blowing machine including a finishing mold 15 mounted on and for rotation with a rotary frame 16, and adapted for vertical swinging movement on trunnions 17 at regular time intervals to alternately position the mold to receive a blank to be expanded and then discharged as 30 a finished article. A serpentine track 14 is provided to control the successively changing positions of the finishing mold. The mold supporting means and operating mechanism may be of any approved or conventional 35 type.

40 The article holder or "knock-out arm" 18 is supported on the upper end of a rock shaft 19 (Figs. 1 and 2) the latter extending downwardly thru a carrier 20 which is formed at the outer end of a supporting arm 21. This arm may be curved substantially thruout its length and is provided with an attaching flange 22 secured by bolts 23 to the finishing mold frame 24. A passageway 25 extends 45 lengthwise of the curved arm 21 thereby providing a conduit for air, which, as will be hereinafter apparent, is directed thru the holding or "knock-out" disks to the interior of articles such as bottles "B" in the finishing 50 mold 15.

55 The carrier 20 (Fig. 3) includes an elongated tubular housing 26 the upper portion of which provides a bearing for a sleeve 27 which encloses an intermediate portion of the shaft 19 and may be secured to the latter by a pin 28 or some similar fastener. This sleeve is for the greater part spaced from the shaft (Fig. 3) to provide a chamber in which a coil expansion spring 61, hereinafter 60 described, is placed. The lower portion of the sleeve 27 is formed with a circumferential series of gear teeth 29 running in mesh with a rack bar 30. This rack bar is reciprocated at regular time intervals by mechanism hereinafter described, to impart an oscillatory

movement to the rock shaft 19 and thereby correspondingly move the holding arm 18.

70 The rock shaft 19 which carries said arm 18 is formed with an axial passageway 31 communicating at its upper end with a conduit 32 extending lengthwise of the holding arm 18 and leading to outlet openings 33 extending through the centers of the knock-out disks 34. The other end of the axial opening 31 in the rock shaft 19 communicates thru a series of radial ports 35 with an arcuate recess 36 formed in the exterior face of the sleeve 27. This recess 36 is at all times in register with a port 37 in the housing 26 leading directly to the conduit 25 which extends lengthwise of the curved supporting arm 21 (Figs. 1 and 4). Thus air which is directed into the passageway 25 or chamber in the supporting arm 21, by a means hereinafter described, may be conducted to the outlet orifices 33 in the holding disks 34 for application internally of articles in the finishing molds 15. The knock-out disks 34, or article holding devices, may be supported at the outer end of the holding arm 18 in any approved fashion, and may be adjustable in a well known manner to control and time the discharge of the articles from the corresponding finishing mold. Also the block 38 (Figs. 3 and 4) connecting the holding arm to the rock shaft may be adjusted lengthwise of said shaft 19 to meet varying operating conditions, such for example, as a change in the height of bottles being produced.

90 The rack bar 30 (Figs. 3, 4 and 9) heretofore referred to as comprising part of the mechanism employed to oscillate the rock shaft 19 is arranged in a slideway 39 in one face of the carrier 20, said slideway extending a considerable distance to one side of the tubular housing 26 and above a piston motor to be described. The rack bar 30 is provided with an additional series of gear teeth 40 arranged at right angles to teeth which run in mesh with the teeth 29 or pinion at the lower end of the sleeve 27. This additional series of teeth 40 runs in mesh with a pinion 41 arranged above said rack bar 30 and journaled on a shaft 42 whose ends are mounted in bearings 43 (Fig. 4). One of these bearings 43 is formed in a cover plate 44 removably attached to the carrier 20 and serving to retain the gear and rack bar in operative relation to each other and afford protection to the parts therebeneath.

105 A piston motor 45 arranged below the rack bar 30 and pinion 41 provides means to oscillate the pinion 41 at regular time intervals. This piston motor 45 includes a cylinder 46 extending parallel with the rock shaft 19 and enclosing a piston 47, the latter having a boss 48 formed on its upper face. A rack bar 49 is connected to the boss 48 and extends upwardly thru a slideway 50 (Figs. 5 and 8) 110 in the carrier 20 and along side of the pinion 115 50 in the carrier 20 and along side of the pinion 120 50 in the carrier 20 and along side of the pinion 125 50 in the carrier 20 and along side of the pinion 130

41, the teeth of said rack bar running in mesh with the pinion. A coil spring 51 encircling said boss 48 and a portion of the rack bar 49, operates to normally yieldingly hold the piston 47 in its lowermost position so that the holding arm 18 and holding disks 34 carried by the latter will normally be inoperatively positioned. This coil spring 51 also functions as a safety device, in that it at 10 all times exerts a downward pressure on the piston 47 and as a result tends to retain the holding arm 18 in its outermost or inoperative position at one side of the mold 15. The extent of upward movement of the rack bar 49 is controllable by a stop with which the upper end of the rack bar contacts when the latter reaches the uppermost limit of its stroke. This stop (Fig. 3) comprises a set screw 52 and a lock nut 52^a, the latter operating to hold the set screw or stop in any adjusted position. Provision of this stop facilitates adjustment to obtain accurate positioning of the holding disks upon the articles in the molds, as will be apparent.

The lower end of the cylinder 46 of the piston motor 45 is closed by a removable head 53, the latter providing means permitting ready access to the interior of the cylinder. An air inlet port 54 extends thru one side of the cylinder 45 near its lower end and leads to a chamber 55 to which air under pressure is supplied thru a pipe 80 from a tank (not shown). A needle valve 56 regulates the inflow of air under pressure to the motor cylinder 46. The foregoing structure provides means for moving the knock-out arm 32 laterally in a fashion to bring the knock-out disks 34 into position over and in register with the open upper ends of articles in the finishing molds 15 at regular time intervals.

Mechanism to be now described, includes means for imparting axial movement to the rock shaft 19 and holding arm 18 whereby the disks 34 are alternately moved into and out of contact with the upper ends of articles such as bottles "B" in the molds. A thrust bearing 60 is arranged at the lower end of the rock shaft 19 and supports the lower end of a coil expansion spring 61 which for the greater part is positioned within the sleeve 27. This spring encircles the rock shaft 19 and exerts an upward pressure on the sleeve 27 and shaft 19 so that the latter and the holding disks 34 are normally yieldingly held in their uppermost positions in a plane above the upper ends of the bottles "B". The lower end of the rock shaft 19 carries an extension 62 projecting into a sleeve 63, the latter slidingly arranged in the lower end of the tubular housing 26. A stop finger 64 is mounted on a pin 65 projecting radially from the extension 62, said finger extending 65 into an arcuate recess 66, the end walls of the

latter functioning as stops limiting the swinging movement of said stop finger 64.

One end wall of the arcuate slot or recess 66 (Figs. 10 and 11) comprises a pair of tapered blocks 67, one of which is held against movement lengthwise of the cylinder 26 by a lock nut 68 while the other block is capable of vertical movement by means of an adjusting screw 69. By moving said other block vertically after the lock nut 68 has been released, the first named wedge block is adjusted in a direction transversely of its length to change the length of the arcuate path thru which the stop finger 64 moves. Thus, oscillatory movement of the knock-out arm 32 may be further controlled to thereby provide additional insurance against improper contact between the disks and articles in the finishing molds. A lock screw 57 (Fig. 9) prevents accidental displacement of the stop finger. A cover plate 59 or guard is placed over the slot 66.

The short sleeve 63 (Fig. 9) in the lower end of the housing 26 is formed with an arcuate slot 70 extending circumferentially of the sleeve. The pin 65 which carries the stop finger 64 projects thru this slot. Such construction allows circumferential movement of the stop finger 64 and pin 65 independently of the sleeve 63 so that the cam roll 72 will at all times be positioned for engagement with the cam 73 as will be apparent the latter adapted to move the rock shaft 19 in the direction of its length. This sleeve 63 is formed with a depending finger 71 carrying a cam roll 72 (Figs. 2 and 9), the latter adapted for engagement at regular time intervals with the stationary cam 73. A key 58 (Fig. 9) prevents rotation of the sleeve 63 about the extension 62. The cam 73 is so positioned with respect to the discharge station and the point at which the disks are brought in register with the upper ends of bottles "B" in the finishing molds, that the rock shaft 19, as above stated, is moved axially by said cam to cause engagement between the disks 34 and bottles just prior to opening of the finishing molds 15.

Supply of air under pressure to the piston motor 45 and holding disks 34 is regulated and controlled by a valve mechanism actuated by stationary cams and including a valve casing 75 or housing (Figs. 1, 2 and 7) which is mounted upon and rotates with the mold carriage 16.

Within the valve casing (Fig. 7) and at one side thereof is a pair of vertically spaced valves 77 and 77^a carried by an upwardly projecting stem 83^a, the latter extending thru a guide opening in the upper wall of the casing 75. A coil spring 78 exerts an upward pressure upon the lower valve 77^a tending to move the latter to close the upper side of the chamber 76^a. The upper valve 77, when seated as shown in Fig. 7, closes the lower side 130

of the upper chamber 76. A bell crank lever 82 is pivoted to a hinge pin 83 above the casing 75 and has one end contacting with the upper end of the valve stem 83^a. The other end of the lever 82 carries a cam roll 84 riding upon a stationary cam 85 which is shaped to rock said lever in such a fashion that at times it effects seating of the upper valve 77 and at other times allows the spring 78 to 10 expand and thereby unseat said upper valve 77 and seat or close the lower valve 77^a.

The lower chamber 76^a (Fig. 7) is connected to a supply pipe 79 leading from any suitable source of supply for air under pressure, 15 such air being constantly supplied to the lower chamber 76^a. A flexible pipe 80 (Figs. 6, 2 and 4) leads from a point between the valves 77 and 77^a to the lower end of the motor cylinder 46. A bleed opening 81 is formed in the 20 wall of the upper chamber 76 and is connected to a pet-cock 81^a (Fig. 6).

When a mold group approaches the discharge station (not shown) the cam 85 causes 25 rocking of the bell-crank lever 82 thereby swinging the outer end of the latter downwardly and thereby opening the lower valve 77^a and closing the upper valve 77. While the valves are so relatively positioned, air under pressure flows from the chamber 76^a 30 thru the flexible pipe 80 to the lower end of the piston motor cylinder. The piston 47 is raised by the air under pressure and thru the series of rack bars and pinions (Figs. 3 and 5) heretofore described swings the holding arm 18 from its normal position at one 35 side of the mold 15, to a position over the mold to thereby bring the holding disks 34 into register with the bottles "B". After the disks have been seated upon the bottles and then 40 unseated, in a fashion to be described presently, the bell-crank lever 82 is rocked to allow upward movement of the valves 77 and 77^a under influence of the coil spring 78. This valve movement seats the lower valve 77^a 45 shutting off supply of air under pressure to the pipe 80 and providing communication between the pipe 80 and the upper chamber 76 which leads to the bleed opening 81. With the valves in the positions just stated, the air 50 below the piston 47 (Fig. 3) is exhausted thru the pipe 80 and bleed opening 81. Expansion of the coil spring 51 (Fig. 3) within the motor cylinder 46 increases the rate of exhaust of air from the cylinder 46 and actuates the 55 rack bars and pinions in a fashion to swing the holding arm 18 to its original position at one side of the corresponding finishing mold 15.

The valve casing 75 (Fig. 7) also includes 60 a pair of vertically spaced chambers 86 and 86^a separated from the chambers 76 and 76^a above referred to by a partition 75^a. A valve 90 is arranged within the lower chamber 86^a and carries a stem 93 extending upwardly 65 thru the casing 75 and contacting with a lever

95 pivoted to the hinge pin 83 and carrying a cam roll 96 which rides upon a stationary cam 97. A coil spring 94 arranged in the lower chamber 86^a exerts upward pressure upon the valve 90 and tends to hold said valve 70 upon the seat 92 to thereby prevent communication between the upper and lower chambers 86 and 86^a. The lower chamber 86^a is provided with an inlet opening 87 communicating with a supply pipe 88 leading to any suitable source of air pressure supply (not shown). The upper chamber 86 is formed with an outlet opening 91 communicating with a flexible pipe 89 (Figs. 6, 1 and 2). This pipe 89 leads to the chamber 25 (Fig. 4) which in turn communicates by way of ports 35 leading to an axial opening 31 in the rock shaft 19 with axial openings 33 in the holding disks 34. This opening 31 in turn leads to a passageway 32 extending lengthwise of the holding arm 18.

After, or simultaneously with, seating of the holding disks 34 upon the bottles "B" as above described, the rock arm 95 is moved downwardly by the cam 97 to unseat the 90 valve 90 and thereby establish communication between the lower chamber 86^a and the upper chamber 86. Air under pressure may then flow into the upper chamber 86 and thence thru the flexible pipe 89 and passageways which lead from said pipe to the axial 95 openings 33 in the holding disks 34. This air is then directed into the bottles "B" to chill and thereby set the glass. Upward swinging movement of the rock arm 95 allows the coil spring 94 to expand and thereby seat the valve 90 and shut off flow of air under pressure into the upper chamber 86. After the disks are lifted away from the bottles 100 the air under pressure within the pipe and passageways between the disk and chamber 86 is exhausted thru the ports 33 in the disks.

The operation may be briefly reviewed as follows: The finishing molds 15, which are ordinarily arranged in an annular series rotating about a vertical axis, are brought one at a time to a discharge station, in advance of which the molds are opened, so that articles of glassware, such as bottles "B" may be ejected from the molds 15 at said station. 110 A short distance in advance of the discharge station, the cam 85 (Figs. 6 and 7) rocks the lever 82 to open the valve 77 so that air under pressure is applied to the lower side of the piston 47 of the air motor 45. 115 Thus, the piston is moved upwardly and thru the rack bars and pinion referred to swings the knock-out arm 18 laterally, bringing the holding disks 34 to position over and in proximity to the upper ends of the bottles "B" in the mold 15. Immediately following such positioning of the disks 34 the cam 73 moves the rock shaft 19 axially downward thereby snugly seating the holding disks 120 upon the upper ends of the bottles. The out- 125 130

let orifices 33 in said disks are brought into register with the open ends of the bottles by such movement. Substantially simultaneously with contact between the disks and bottles or at a later period if desired, the cam 97 (Figs. 2 and 7) rocks the lever 95 to open the valve 90, so that air will flow into the conduit 89 and thence into and thru the passageway 25 from which the air enters the axial opening 31 in the rock shaft 19 and flows upwardly and outwardly thru the conduit 32 to the outlet orifices 33 in said holding disks. Thus, air is applied internally of the articles in the molds and operates to set the glass comprising the articles to a certain degree prior to their discharge from the molds. The cam 73 (Figs. 2 and 2A) located adjacent the serpentine track 14, is so shaped that it allows the spring 61 to raise the holding arm 18 and thereby remove the disks 34 from contact with the bottles "B" after the finishing molds 15 have opened so that the bottles may be discharged from the molds at the proper point or points. The cam 85 (Figs. 2 and 7) operates, after discharge of the bottles, to shut off the supply of air under pressure to the lower end of the piston motor cylinder 46 and so moves the valves 77 that the conduit 80 is opened thru the upper end of the chamber 76 to the atmosphere. This allows exhaust of air from the lower end of the motor cylinder 46 to the atmosphere. The expansion coil spring 51 is now free to move the piston 47 downwardly, and does so, with the result that the rack bars and pinions heretofore described are actuated to return the holding arm 18 to its normal position at one side of the corresponding finishing mold 15. From the above it is evident that it is unnecessary to swing the holding arm 18 from one position to another at an excessive rate as by the cam heretofore employed, the result being that very little strain and wear are imposed upon the moving parts of the article holding mechanism. This is in direct contrast to conditions existing where the rate of movement of the arm is excessive, because of the necessarily short quick acting cam employed to oscillate said arm.

In the event of the holding disks 34 seating off center upon the bottles so that they do not properly hold the bottles, or do not allow injection of air into the latter, the stop screw 52 may be adjusted to change the length of the stroke of the rack bar 49 and piston 47, or the wedge blocks 67 (Figs. 10 and 11) may be adjusted to increase or decrease the extent of the swinging movement of the arm 18 to the degree necessary to obtain proper seating of the disks. Both adjustments may of course be made if found desirable.

When the cam roll 72 (Fig. 2) passes beyond the cam 73 (Figs. 2A and 2B) the rock shaft 19 is lifted by the coil spring 61 there-

by raising the holding disks 34 away from the bottles. The bottles immediately fall by gravity into a chute (not shown) for delivery to any approved type of ware handling mechanism (not shown). Varying conditions may require changes of greater or less degree in the exact point of discharge of the articles. This is obtained by slidingly supporting the cam 73 on a stationary bracket 100 (Figs. 2A and 2B). A cam carrier 101 is interposed between the cam 73 and bracket 100 and is provided with rack teeth 102 on its inner face running in mesh with a pinion 103. This pinion is secured to the upper end of a shaft 104 carrying a worm gear 105 which meshes with a worm 106. The worm and gear are enclosed in a housing 107 suspended from the stationary bracket 100 heretofore referred to. An operating rod 108 has one end connected to the worm 106 and as shown may be composed of sections secured together by universal joints, for obvious reasons. A hand wheel 109 is provided to permit manual rotation of the rod whereby the cam 73 may be moved in the direction of its length. Such movement of the cam changes the point at which the cam roll 72 moves beyond the influence of said cam and as a result correspondingly varies the point at which the holding disks 34 move upwardly away from the bottles to permit discharge of the latter from the molds 15.

Modifications may be resorted to within the spirit and scope of the appended claims.

What I claim is:

1. The combination with a finishing mold, of a holding arm to engage an article in the mold and hold it during opening of the mold, a carrier on which said arm is mounted, a rock shaft providing connection between the arm and carrier, said shaft being capable of axial and oscillative movement in the carrier, a piston motor, means including a series of rack bars and pinions operated and controlled by said motor to oscillate the shaft and thereby position the arm over said article and at one side thereof in alternation, and cam mechanism operable independently of said motor, rack bars and pinions to impart axial movement to the shaft and thereby periodically cause engagement between the arm and the article in the mold.

2. The combination with a finishing mold, of a holding arm to engage an article in the mold and hold it during opening of the mold, a carrier on which said arm is mounted, a rock shaft providing connection between the arm and carrier, said shaft being capable of axial and oscillative movement in the carrier, a piston motor, means operated and controlled by said motor to oscillate the shaft and thereby position the arm over said article and at one side thereof in alternation, cam mechanism to impart axial movement to the shaft and thereby periodically cause engage-

ment between the arm and the article in the mold, said cam mechanism operable independently of said motor and the said means operated thereby, and means to apply air internally of the article while said arm is positioned over the latter.

3. The combination with a finishing mold, of a holding device to engage an article in the mold and hold it during opening of the mold, 10 a piston motor, means including rack and pinion mechanism operated and controlled by said motor to move the holding device laterally to the position over the article, cam actuated means operable independently of 15 said motor mechanism, for moving the holding device downwardly into engagement with said article, and adjustable means to control the extent of movement caused by operation of the motor to thereby predetermine the 20 operative position of the holding device relative to the article in the mold.

4. The combination with a finishing mold, of a holding device to engage an article in the mold and hold it during opening of the mold, 25 a piston motor, a rack bar constituting a piston rod for said motor, means operated and controlled by movement of the rack bar to move the holding device laterally to a position over the article, and means independent 30 of the piston motor to move the holding device into engagement with said article.

5. The combination with a finishing mold, of a holding device to engage an article in the mold and hold it during opening of the mold, 35 a piston motor, a rack bar constituting a piston rod for said motor, means operated and controlled by movement of the rack bar to move the holding device laterally to a position over the article, and cam mechanism operable independently of the motor to move 40 the holding device into engagement with said article.

6. The combination with a finishing mold, of a holding device to engage an article in the mold and hold it during opening of the mold, a piston motor, a rack bar constituting a piston rod for said motor, means operated and controlled by movement of the rack bar to move the holding device laterally to a position over the article, means independent of 45 the piston motor to move the holding device into engagement with said article, and an adjustable stop controlling the extent of movement of the rack bar and thereby predetermining the final operative position of the holding device with respect to the article in the mold.

7. The combination with a finishing mold, of a holding device to engage an article in the mold and hold it during opening of the mold, a piston motor, a rack bar constituting a piston rod for said motor, means operated and controlled by movement of the rack bar to move the holding device laterally to a position over the article, means independent of 55

the piston motor to move the holding device into engagement with said article, and yielding means included in the piston motor normally tending to position the holding device at one side of said mold.

8. The combination with a finishing mold, of a holding device to engage an article in the mold and hold it during opening of the mold, a piston motor, a rack bar constituting a piston rod for said motor, means operated and controlled by movement of the rack bar to move the holding device laterally to a position over the article, means independent of the piston motor to move the holding device into engagement with said article, and yielding means included in the piston motor normally tending to position the holding device at one side of said mold, said last named means including a coil expansion spring encircling said rack bar within the piston motor.

9. The combination with a finishing mold, of a holding device to engage an article in the mold and hold it during opening of the mold, means including a series of racks and pinions to move the holding device laterally to a position over said article, and means independent of the racks and pinions for moving the holding device downwardly into engagement with said article.

10. The combination with a finishing mold and means for moving said mold in a closed path, of a holding device mounted for movement in a closed path with the mold, said holding device adapted to engage an article in the mold and hold it during opening of the mold, a piston motor, means operated and controlled by said motor to move the holding device laterally to a position over the article, cam actuated means to move the holding device downwardly into engagement with the article, a cam brought by movement of the mold into engagement with said means for moving the holding device downwardly into contact with the article, and means for adjusting the cam to vary the point of initial contact of the holding device with said article.

11. The combination with a finishing mold and means for moving the mold in a closed path, of a holding device mounted for movement in a closed path, an arm supporting said holding device, a rock shaft extending alongside and lengthwise of the mold and connected at its upper end to said arm, a carrier in which the rock shaft is mounted for oscillation and reciprocation, means for oscillating and reciprocating said rock shaft and arm to thereby periodically place said device in contact with an article in the finishing mold, said carrier having a slot extending lengthwise in one wall, a radial finger carried by the rock shaft and extending into said slot, and means for changing the spaced relation between opposed longitudinal walls of the slot

to thereby vary the degree of oscillatory movement of the shaft.

12. The combination with a finishing mold and means for moving the mold in a closed path, of a holding device mounted for movement in a closed path, an arm supporting said holding device, a rock shaft extending alongside and lengthwise of the mold and connected at its upper end to said arm, a carrier 10 in which the rock shaft is mounted for oscillation and reciprocation, means for oscillating and reciprocating said rock shaft and arm to thereby periodically place said device in contact with an article in the finishing mold, 15 said carrier having a slot extending lengthwise in one wall, a radial finger carried by the rock shaft and extending into said slot, one longitudinal wall of the slot comprising a pair of tapered blocks, and means for adjusting the blocks relative to each other to thereby 20 change the width of the slot and correspondingly vary the degree of oscillatory movement of the rock shaft.

Signed at Toledo, Ohio, this 31st day of
25 October 1928.

JOHN E. McLAUGHLIN.
